UNITED STATES PATENT OFFICE.

RICHARD K. ROACH, OF WILLARD, NEW YORK.

COMBINED SPIRIT-LEVEL AND PLUMB-BOB.

1,179,219.

Specification of Letters Patent. Patented Apr. 11, 1916.

Application filed August 26, 1914. Serial No. 858,721.

To all whom it may concern:

Be it known that I, RICHARD K. ROACH, a citizen of the United States, residing at Willard, in the county of Seneca and State 5 of New York, have invented new and useful Improvements in Combined Spirit-Levels and Plumb-Bobs, of which the following is a specification.

This invention relates to a combined spirit 10 level and plumb bob, and it has for its object to produce a simple device of this class which may be conveniently used in either capacity.

A further object of the invention is to 15 produce a combined plumb bob and spirit level having a simple and improved attaching device whereby it may be quickly and conveniently connected with or detached from a suspending cord.

With these and other ends in view which will readily appear as the nature of the 20 invention is better understood, the same consists in the improved construction and novel arrangement and combination of parts 25 which will be hereinafter fully described and particularly pointed out in the claims.

In the accompanying drawing has been 30 illustrated a simple and preferred form of the invention, it being however, understood that no limitation is necessarily made to 35 the precise structural details therein exhibited, but that changes, alterations and modifications within the scope of the claims may be resorted to when desired.

In the drawing,—Figure 1 is a perspective 40 view, showing the device in use as a plumb bob. Fig. 2 is a side elevation, showing the device in use as a spirit level. Fig. 3 is a transverse sectional view taken on the line 3—3 in Fig. 2. Fig. 4 is a longitudinal sectional view taken on the line 4—4 in Fig. 3.

Corresponding parts in the several figures are denoted by like characters of reference.

The improved plumb bob comprises a 45 casing 15 which is preferably rectangular in cross section, although no limitation is made in this respect. The casing has a detachable lid 16 which may be held in position by fastening means, such as screws 17. The two sides of the casing are provided 50 with sight openings 18, and the lid 16, likewise, has a sight opening 19. A conical

member 20 serving as a pointer or indicator is attached to one end of the casing 15 in 55 substantially axial alignment therewith. The other end of the casing is provided with a hook member comprising a shank 21 which is threaded into the casing and is provided at its outer end with a V-shaped 60 hook 22 and into which the looped end of a cord 23 may be quickly adjusted and where said cord will be quickly and accurately centered by the action of the convergent side members of the V-shaped hook 65 the apex of which lies in the longitudinal axis of the device.

A spirit level 25 is mounted in the casing 15 where it may be secured by a filling 26 of plaster of Paris or other suitable material of a plastic nature which will enable 70 the level to be held securely without obstructing the sight openings.

The operation and advantages of this invention will be readily understood from the 75 foregoing description, taken in connection with the drawing.

When the device is to be used as a plumb bob, it is connected with the suspending cord 23. For use as a level it may be 80 quickly detached from the cord and used in the well known manner of an ordinary spirit level.

Having thus described the invention, what is claimed as new, is:—

1. A device of the class described comprising a casing, substantially square in cross section and including a bottom member, an end member, side members and a lid, said side members and lid being provided with sight openings, a conical indicator fitted in the open end of the casing, fastening members connecting the lid with the end member and with the conical indicator, and a spirit level inset in the casing 95 and visible through the sight openings.

2. A device of the class described comprising a casing, substantially square in cross section and including a bottom member, an end member, side members and a lid, said side members and lid being provided with sight openings, a conical indicator fitted in the open end of the casing, fastening members connecting the lid with the end member and with the conical indicator, and a spirit level inset in the casing 100 105

and visible through the sight openings; and
an attaching member consisting of a shank
threaded into the end member and having
a V-shaped hook, the apex of which lies
5 in the longitudinal axis of the device
whereby a looped cord connected therewith
will be automatically centered.

In testimony whereof I affix my signature
in presence of two witnesses.

RICHARD K. ROACH.
